UNITED STATES PATENT OFFICE.

WILLIAM S. WILSON, OF BALTIMORE, MARYLAND.

BASE-BALL GAME.

1,118,323.

Specification of Letters Patent. Patented Nov. 24, 1914.

Application filed February 18, 1914. Serial No. 819,387.

To all whom it may concern:

Be it known that I, WILLIAM S. WILSON, a citizen of the United States of America, at present residing at Baltimore, Maryland, have invented certain Improvements in 5 Base-Ball Games, of which the following is a specification.

In the description of the said invention which follows, reference is made to the accompanying drawings, forming a part hereof, and in which:—

Figure 1 is a perspective top view of the improved baseball game, and Fig. 2 an enlarged perspective top view, partly in section, of certain parts of the apparatus, illustrating the mechanism whereby the game is played. Fig. 3 is a perspective underside view of a portion of Fig. 2; and Figs. 4, 5 and 6 are still further enlarged perspective 20 views of parts of the apparatus.

Referring now to the drawings, 1 is the foundation plate of the apparatus, and 2 a board which represents the baseball field. It is supported from the foundation plate 15 by the stands 3. Upon the field board, are marked lines *a* which bound the diamond 4, and centrally of the diamond, is a fixed disk 5 which is separated from the remaining portion of the diamond, by a narrow space 25 or channel *b* for a purpose hereinafter described.

7 is a fixed vertical post on the foundation plate 1, terminating in a shaft 9 which extends into a socket 10 on the underside of 35 the disk 5 and shown only in Fig. 3. 12 is an arm the inner end of which fits loosely over the said shaft, in order to allow of its rotation.

13 is a spring coiled about the post 7 with 40 one of its ends attached to the post at *c*, and its other end fastened to the arm 12 at *d*. The function of the spring 13 is to yieldingly retain the arm 12 in alinement with the dotted axial line *a* shown in Fig. 1, and 45 admit of its free end describing a circle around the shaft 9, when force is applied to the arm, in a manner hereinafter described.

Referring now to Fig. 1 it will be seen 50 that there are on the field, a number of fixed figures representing players viz: the umpire, catcher, pitcher, the first baseman, second baseman, right fielder, center fielder, short stop, left fielder, and the third baseman; 55 and in addition to these figures, is the runner represented by 14 who stands on a ver-

tical rod 15 adapted to rotate in the arm 12, and which passes loosely through the slot *b*, with the runner above the field board 2. To the lower end of the rod 15 is secured an ordinary furniture caster 17, the roller *e* of 60 which is placed in the rear of the runner 14, and rests on the foundation plate 1. By this means, the runner will at all times face the direction in which he is running, a result 65 which adds to the realism of the game.

20 is a horizontal bar arranged to slide in a vertical frame 21 situated between the base plate 1 and the field board 2, having at its inner end a triangular head *f* adapted to 70 come in contact with a similarly shaped block *g* on the side of the arm 12 when the same is in its normal position, or that wherein the runner stands at the home plate. The outer end of the bar 20 is provided with a 75 cup *h* in which is held by the ring *i*, the ball 22, of preferably some slightly flexible substance such as rubber, or some hard material covered with leather. The bar 20 is held yieldingly in its extreme outward position 80 by means of a spring 23 which is coiled about it, and compressed endwise between the cup *h* and the frame 21. From this description it will be understood that should the ball 22 be struck a sharp blow, the arm 85 12 will be thrown forward carrying with it the runner 14 who traverses the slot *b* a distance which depends upon the force of the stroke.

Underneath the field board, and situated 90 at each of the three bases, is secured in any suitable manner a segmental block 24 the inner edge of which is in the path of the end of the arm 12. Extending loosely through each of these blocks and a plate *j* fastened 95 thereto, is a stem 25 having at its inner end a catch 27, and at its outer end a knob 29 which is connected by a wire *k* to a ring *m* situated at the edge of the field board and near to the home plate. 100

30 is a spring coiled about the stem 25 and between the catch 27 and the plate *j*, which yieldingly holds the catch in the path of the end of the arm 20 as shown in Fig. 6. The block 24 and its attachments at the home 105 plate is not shown in the drawing. A second spring 31, serves to take up the shock as the returning arm strikes the catch 27.

Should the runner pass a base, the latch thereat prevents his return to the home plate 110 until the latch is drawn outward by the wire *k*; and a run can only be scored by the run-

ner passing all the bases and reaching practically the home plate.

In playing the game, the player using preferably, an ordinary baseball bat, strikes 5 the ball 22 a sharp blow, whereupon the runner who at that time is at the home plate, will run forward traversing the slot 6. Should he pass the first base and stop before reaching the second base, he will fall back 10 to the latter and be held thereat until the latch at the first base is drawn inward by means of the wire attached to the operating stem 25 whereby the latch is detached from the arm 12. The spring 13 will then 15 bring the runner again to the home plate. Such a movement of the runner will of course not count, and it is only when the runner has passed all the bases and is held at the home plate that a run is scored.

20 It will be understood that the runner who during the run described, faces in the direction of his movement, will on his return face about, thus bringing his face toward the home plate, where he will remain until 25 the ball 22 is again struck.

I claim as my invention:—

1. In a baseball game a foundation plate, a field board elevated above the foundation plate having a circular slot extending therethrough, a centrally situated fixed vertical post erected on the foundation plate carrying a loosely pivoted arm, spring mechanism which connects the arm to the fixed post, adapted to yieldingly retain the pivoted arm against rotation about the post, a vertical runner-carrying rod adapted for rotation in the arm, which projects through the said slot, the said rod at its lower end being provided with a caster which rests 40 on the foundation plate, whereby the rod in its change from a forward to a backward movement in the slot is turned on its axis 180 degrees for a purpose described.

2. In a baseball game, a field board having a circular groove or slot which extends therethrough, a fixed central vertical post, an arm loosely pivoted to the post having at its end a rod which passes through the circular slot and carries a figure which represents the runner in the game, combined 45 with an endwise-moving bar which upon being struck, will engage the said arm and cause the runner to traverse the slot, spring mechanism to yieldingly retain the runner 50 adjacent to a point on the board representing the home plate, catches on the field board, spaced around the circular slot therein to limit the backward movement of the runner toward the home plate, and devices 55 to render the catches temporarily inoperative and thereby admit of the complete return of the runner to the home plate position, substantially as specified.

3. In a baseball game, a field board having 60 a circular groove or slot which extends

therethrough, a fixed central vertical post, an arm loosely pivoted to the post having at its end a rod which passes through the circular slot and carries a figure which represents the runner in the game, combined 70 with an endwise-moving bar which upon being struck, will engage the said arm and cause the runner to traverse the slot, spring mechanism to yieldingly retain the runner adjacent to a point on the board 75 representing the home plate, catches on the field board, spaced around the circular slot therein to limit the return movement of the runner toward the home plate, and devices to render the catches temporarily inoperative 80 and thereby admit of the runner reaching the home plate position, substantially as specified.

4. In a baseball game, a field board having a circular groove or slot which extends 85 therethrough, a fixed central vertical post, an arm loosely pivoted to the post having at its end a rod which passes through the circular slot carrying a figure which represents the runner in the game, combined 90 with a spring-retracted endwise-moving bar carrying a ball, which upon being struck, will cause the bar to engage the said arm and thereby force the runner to traverse the slot, spring mechanism to yieldingly retain 95 the runner adjacent to a point on the board representing the home plate, catches on the field board which are spaced around the circular slot therein, to limit the backward movement of the runner toward the home 100 plate, and devices to render the catches temporarily inoperative and thereby admit of the complete return of the runner to the home plate position, substantially as specified.

5. A baseball game, comprising as elements thereof, a fixed vertical post, an arm pivoted to the post and united to the same by means of a coiled spring one end of which is connected to the post, and the other 110 end to the arm, a vertical stem carrying a figure representing a runner, adapted for rotation within the arm, and provided with a caster at its lower end, combined with a plate upon which the caster rests, and means 115 to effect a rotation of the arm around the post, whereby in the forward and backward rotation of the arm the vertical stem is reversed in circumferential position, substantially as specified.

6. A baseball game comprising as elements thereof, a foundation plate, a fixed vertical post erected on the said plate, an arm pivoted to the vertical post, a coiled spring which connects the post with the 120 arm and resists rotation of the latter, combined with a spring-retracted bar one end of which is adapted to engage the end of the rotary arm and cause the forward movement of the same, and the other end pro- 125 130

vided with a cup, a ball, and a ring to hold the ball within the cup, substantially as specified.

7. A baseball game comprising as elements thereof, a foundation plate, a fixed vertical post erected in the plate, a runner-carrying arm pivoted to the post, a spring coiled about the post with one of its ends fastened to the same, and its other end se-

cured to the arm, combined with a spring-¹⁰ retracted arm-actuating bar having at its outer end a cup, a ball, and a ring to hold the ball in the cup, substantially as specified.
